UNITED STATES PATENT OFFICE.

LA FAYETTE D. VORCE, OF SANDWICH, ONTARIO, CANADA.

ELECTROLYTIC CELL.

1,286,844.

Specification of Letters Patent.

Patented Dec. 3, 1918.

Application filed April 2, 1918. Serial No. 226,336.

To all whom it may concern:

Be it known that I, LA FAYETTE D. VORCE, a citizen of the United States, residing at Sandwich, in the Province of Ontario and 5 Dominion of Canada, have invented certain new and useful Improvements in Electrolytic Cells, of which the following is a specification.

This invention relates to electrolytic cells; 10 and it comprises an electrolytic cell having an outer casing, a cathode-supported diaphragm within the casing and spaced apart therefrom to form an alkali-chamber therebetween, a cover or chlorin dome carrying 15 anodes, for the brine chamber within the diaphragm, luglike means on said cover for supporting its weight from the outer casing and a sealing ring carried by the cathode for closing the alkali chamber and making a 20 seal with said cover; all as more fully hereinafter set forth and as claimed.

In principle, all diaphragm electrolytic cells for the manufacture of chlorin and caustic alkali from solutions of alkaline 25 chlorids, such as a solution of common salt (sodium chlorid), are very simple; and the various types now in use do not differ materially from each other, or from the original Hargreaves-Bird cell. In actual construction, in view of the large sized units 30 now in use, many technical difficulties arise in manufacturing a cell which is easy and inexpensive to build and of small cost in upkeep and operation. All such cells have 35 a brine chamber provided with a chlorin outlet and containing one or more anodes and a cathode or alkali chamber, separated from the brine chamber by a pervious wall or diaphragm. In practice the alkali chamber 40 is generally open in the sense of not containing much liquid and the diaphragm is made of asbestos or the like, given mechanical support by a cathode of punched metal (copper or iron) or woven wire. The cells may be, 45 and are, of various shapes and structure; but for simplicity of construction, it is best to make the alkali chamber annular and surrounding a cylindrical brine chamber formed by the cathode and diaphragm. The 50 anodes are best made of a plurality of graphite rods suspended from a cover and placed in annular arrangement as near the diaphragm as may be.

With such a type of cell structural details 55 are highly important in producing an apparatus easy to build and assemble and equally

easy of disassemblage for repairs and cleaning. Simplicity and strength are equally important. Most of the difficulties arise with regard to the diaphragm which must be thin and pervious and yet resist the weight of a considerable body of hot brine which it encloses, without leakage or undue seepage of liquid therethrough. Diametrical strains are of course resisted by the punched or 60 woven metal cathode; but it is in practice not desirable to impose any vertical stress on the ringlike diaphragm and cathode.

In the present invention these conditions are met by carrying all the weight from an 65 outer casing inclosing and forming one wall of the alkali chamber. The cell cover or chlorin dome, carrying the anodes, is supported from and rests on the top of this casing and the weight of the cathode-diaphragm structure (or "cathode pot") and the brine therein is carried from the bottom of this casing. In so doing, it is not necessary to place any substantial weight on the top of cathode and diaphragm; and everything 70 can be readily assembled and disassembled by a lifting crane. In practice, I make this casing open-bottomed, providing it with an inner flange on which is a rim carrying the bottom of the cathode pot. This bottom may 75 be a simple disk of concrete, reinforced or not as the case may be. The cover of the whole structure may also be made of concrete and is so shaped as to close in and seal the cathode pot while its weight is carried 80 by lugs resting on the outer casing; these lugs permitting easy lifting by a crane or the like. In some types of cover now in use, lifting must be by attachment of lifting elements in the chlorin outlet; which is 85 highly undesirable.

In the accompanying illustration, I have shown, more or less diagrammatically, an electrolytic cell within the present invention. As shown, it is of cylindrical shape, although 90 it might as readily be rectangular or another shape. With a cylindrical shape, construction, repair and upkeep are easier. In this showing

Figure 1 is a central vertical section of 105 such a cell, certain parts being shown in elevation; and

Fig. 2 is a fragmental plan view of the top or cover.

As shown the cell comprises a container 110 1 which may be of any suitable metal or material and is provided with an annular

bottom ring 2, which may be flanged out of the metal of the annulus or may be as shown a ring of channel section. A rim flange 3 of this channel-section ring carries the bottom 5 of the cathode pot. It is also provided with outlet 4 for removal of alkali solution. Located within this container is a cathode pot, which as shown is composed of an annular body of perforated or punched metal 5 carrying a diaphragm 6 of asbestos or the like 10 on its inner periphery. Strengthening bands 7 and 8 are provided at the top and bottom. Within this annulus is a bottom 9 which may be of concrete or other suitable 15 material and is provided with a recess or depression 10 to accommodate the upturned flange of the bottom ring of the outer container. At the top it is provided with a ring 11 or the like fitting closely the top of 20 the outer container and making a tight joint therewith by the aid of luting 11' of any suitable kind. The cathode carries current lead 12. So far as described, it will be noted that the cathode pot is located within 25 the outer container and is supported from its bottom. The top ring carried by it fits accurately within the outer container and makes a tight joint therewith, luting being used if necessary. In use the cathode pot 30 is kept filled to a suitable height with a body of brine 13. Within this body of brine depend a plurality of rod-like anodes of graphite or other form of carbon 14 passing through and carried by a head or crown 35 15. As shown, this cover is somewhat smaller in diameter than the outer container and is provided with lugs 16 making it a sort of spider, these lugs resting on the top of the outer container. This structure 40 makes it convenient in use since it enables a crane to pick it up readily. The bottom of the cover is near the top of the upper ring and a tight joint therebetween is readily made by the use of a little lute. As 45 shown, the cover is domed upwardly in the center, to chlorin outlet 17. Around this outlet the top of the cover is flanged at 18 to provide a convenient seal for connecting with a vertical chlorin conduit (not shown).

50 Current is supplied to the anodes through connections 19. Brine may be supplied to the body of electrolyte in the cell by conduit 20 provided with level adjusting overflow 21 and fed from a suitable source of brine 22.

55 What I claim is:—

1. In an electrolytic cell, a casing, a diaphragm-carrying cathode therewithin and forming a partition between a cathode chamber and an electrolyte chamber, an 60 anode within the electrolyte chamber, and a

cover sealing the top of the electrolyte chamber and carrying said anode, said cover being supported by the top of said casing.

2. In an electrolytic cell, a casing, a diaphragm-carrying cathode therewithin and forming a partition between a cathode chamber and an electrolyte chamber, an anode within the electrolyte chamber, and a cover sealing the top of the electrolyte chamber and carrying said anode, said cover having projections resting on and supported by the top of said casing.

3. In an electrolytic cell, a casing open at the top and bottom, said bottom having an inturned rimmed flange, an inner hollow metal cathode carrying a diaphragm and spaced away from said casing, a bottom for the space within the cathode resting on said rimmed flange, a sealing ring carried by the top of the cathode closing the space 80 between the cathode and casing, a cover resting on the casing and supported thereby and adapted to seal with said ring and anodes within the electrolyte chamber carried by said cover.

4. In an electrolytic cell, a casing, a diaphragm-carrying cathode spaced from said casing and forming a partition between a cathode chamber and an electrolyte chamber, a sealing ring carried by the top of the cathode closing the space between the cathode and casing, a cover supported by the casing and anodes within the electrolyte chamber carried by said cover.

5. In an electrolytic cell, a casing, a diaphragm-carrying cathode spaced from said casing and forming a partition between a cathode chamber and an electrolyte chamber, a sealing rim carried by the top of the cathode and closing the space between the cathode and casing, a cover, lugs formed on the cover and resting on the casing and an anode within the electrolyte chamber carried by said cover.

6. In an electrolytic cell, a casing open at the top and bottom, an inner hollow metal cathode carrying a diaphragm and spaced from said casing, a bottom wall for the space within the cathode supported at and by the bottom of said casing, a sealing ring carried by the top of the cathode closing the space between the cathode and casing, and a cover resting on the casing and supported thereby and adapted to seal with said ring and anode within the electrolyte chamber carried by said cover.

In testimony whereof I affix my signature hereto.

LA FAYETTE D. VORCE.
